UNITED STATES PATENT OFFICE

JOHN J. O'CONNOR, OF ROCK ISLAND, ILLINOIS

PROCESS FOR MAKING MIXED WATER GAS AND COAL GAS

Original application filed October 12, 1921, Serial No. 507,288. Divided and this application filed April 14, 1923, Serial No. 632,007. Renewed April 8, 1929.

The purpose of this invention is to provide an improved process for producing combustible gas composed of a mixture of so-called "water gas" and "coal gas", utilizing such carbonaceous material as bituminous coal, coke, lignite, and the like, and which shall not only produce the gas more cheaply than it is now being manufactured by apparatus in common use, but shall also operate efficiently on a small scale, so that the process is well adapted to be employed in an individual plant of any large commercial user of gas for heating or power. The process consists in the various steps and features hereinafter described as practiced in apparatus of the type shown in the drawings and in accordance with the attendant claims.

In the drawings, which are diagrammatic:

Figure 1 is a top plan view of an apparatus adapted for this process, showing only the parts above the section line 2—2 on Figure 3.

Figure 2 is a transverse section of the apparatus taken as indicated at the line 2—2 on Figure 3.

Figure 3 is an elevation of said apparatus.

For understanding the process, it is desirable first to describe the apparatus indicated by the drawings. This consists of a pair of twin gas generators, 1 and 2, which are structurally similar and contain the usual grate bars and fire pots common in gas generators, as more fully illustrated in my co-pending application, Serial No. 507,288, filed October 12, 1921, of which this application is a division.

The generators are coupled together both above and below the fire pot or combustion zone by pipes, 3 and 4, respectively, provided with valves, 5 and 6, whereby the flow of gas from one generator to the other may be controlled as to its path.

Each generator also has upper and lower discharge or off-take pipes, 7 and 8, respectively, leading to water seals, 9, from which the gas outlet pipes, 10, may be understood as connecting with a common gas holder, not shown. Each generator also has a steam supply connection, 11, with inlets, 12 and 13, opening into the generator respectively above and below the fire pot; and, in addition, each

of the steam lines is fitted with an air mixer, 14, connected in a by-pass pipe, 15, so that either steam alone or a mixture of air and steam may be injected at 12 or 13, as desired. Suitable valves are shown in these pipe connections for directing and controlling the steam supply. 55

An air blast pipe, 16, has branches 17, each controlled by a valve, 18, for supplying air to either of the generators at will. 60

Ordinarily, the connections described are adequate for producing fuel gas of various qualities, but when illuminating gas is required, the proper enrichment is secured by the addition of such material as tar, fuel oil, 65 or the like, supplied through injectors at 19, in the top of each generator.

The operation of the process is as follows:

Up-run operation

The fuel chambers or fire pots of the two generators, 1 and 2, are filled to a height of about nine feet with carbonaceous material,—for example, bituminous coal, preferably broken to "nut" coal size. A fire being started in one of the generators, say the chamber 1, the charging doors, 20, are closed; the valves, 5 and 6, are closed, and the valves 21, 22, and 23, are closed. The blast controlling valve, 18, leading to the generator, 1, is open, so that an air blast is supplied to the fuel to induce and accelerate the combustion until the body of fuel becomes incandescent, reaching a temperature of from 2,000° F. to 2,500° F., which, according to experience, is the best 75

temperature for making what is called "blue water gas". It may be understood that while an air blast is at present the most economical means of inducing combustion, there may be some certain conditions under which substantially pure oxygen or ozone might be supplied for this purpose, or other chemical reagents might be employed to react with the carbonaceous material to bring it to incandescence. During this operation, the 80 cap valve, 24, which surmounts the stack, 25, leading from the gas off-take pipe, 7, is left open, so that the gaseous products of combustion, during this "blowing up" process, passes out through the stack. 85

When the desired temperature is reached, the air blast is shut off at the valve, 18, and the cap valve, 24, is closed. The valve, 5, connecting the two generators is opened, and the valve, 26, in the off-take, 8, of the generator, 2, is opened to give access to the water seal, 9. The cap valve, 27, and the valves 28 and 29, are closed to confine the out-flow of gas to the path through the valve, 26.

10 Steam is now admitted to the generator, 1, at the lower inlet, 13, below the grate, so that, as the steam passes up through the hot fuel bed, it is decomposed and united with the carbon, forming hydrogen gas, carbon monoxide and methane. These hot gases, having a temperature of from 1,300° F. to 1,800° F., pass into the chamber, 2, through the valve, 5, and are drawn downward through the mass of fresh fuel therein, tending to coke it and drive off the volatile matter, which unites or mixes with the water gas coming from the generator, 1. The resultant combustible mixed gas passes through the grate of the generator, 2, and out through the valve, 26, into the water seal, 9, and thence through the outlet, 10 to a gas holder.

Down-run operation

After a gas-making period of from three to five minutes, during which the temperature in the generator, 1, may drop as low as 1,500° F., the steam is shut off and the valve, 5, is closed. The air blast or other oxidizing means is again admitted by the valve, 18, for reheating the fuel bed to about 2,500° F., with the cap valve, 24, open. When this temperature is again attained, the air blast is shut off and the stack valve is closed. Then the valve, 6, is opened and steam is admitted to the generator, 1, at the upper opening, 12, so as to drive the gaseous products downward through the fuel bed out past the valve, 6, and upward through the partially coked fuel in the generator, 2. The combustible gas thus produced is led out through the off-take, 7, and, with the valve, 26, closed, and the valve, 29, opened, passes into the water seal, 9, and thence through the outlet, 10, to a gas holder.

More gas is made in this down-run than in the up-run because of the natural tendency of the hot gas or steam to rise, whereas the admission of steam at the upper inlet, 12, forcing the gaseous products to take a downward course through the fuel, retards its movement, so that the gas remains longer in operative contact with the incandescent fuel mass and acts upon surfaces of the fuel which were not attacked in the preceding up-run. The down-run is also more effective than the up-run because it tends to carry the ash and clinker down toward, and through, the grate; making the fire easier to clean and rendering the incandescent mass freer from the blanket-ing effect of the ash which would otherwise

accumulate as the combustion and decomposition proceed.

Reversal

After from six to ten gas-making runs have been made in alternate directions,—as above described,—making water gas in the generator, 1, and passing it through the coal in the chamber, 2, said coal will be thoroughly coked and the fuel in chamber, 1, will be practically exhausted. Said chamber, 1, is then recharged with fresh coal or other fuel through the charging door, 20, the cap valve, 24, remaining open, if desired, to relieve any gas pressure in said chamber. At the same time, the valves, 5 and 6, being both closed, the cap valve, 27, corresponding to the generator, 2, is opened and the air blast is admitted to said generator through the valve, 18. The steam being shut off, the coked fuel in chamber, 2, is now "blown up" to incandescence to prepare for making water gas in this generator.

When the desired temperature is attained in the chamber, 2, the cap valve, 27, and the air blast valve, 18, are closed and the valve, 5, may be opened and the steam up-run operation will proceed in the generator, 2, furnishing water gas to the fresh fuel in the chamber, 1, for coking it and delivering the resulting gas at the lower outlet, 8,—the valve, 21, being opened and the valves, 22 and 23, being closed for directing this gas through the water seal, 9, and outlet, 10, to the gas holder. It will be understood that in this up-run of the generator, 2, the steam is admitted to said generator at 13 in the same manner as described for the up-run of the generator, 1.

After the up-run has cooled the fuel bed in the chamber, 2, the valve, 5, is closed and the fuel is again "blown up" with the air blast, whereupon a down-run is made by admitting steam at the upper inlet, 12, of chamber, 2, and passing the gas out through the valve, 6, and up through the partially coked fuel charge in chamber, 1.

After a number of up and down runs in the generator, 2, with delivery of the gas through the off-take, 7, or the off-take, 8, of the chamber, 1, the fuel in chamber, 2, will become exhausted and the fuel in chamber 1,—by this time fully coked,—may be heated to incandescence with an air blast and the process again reversed with a fresh charge of fuel in the generator, 2. It is thus evident that the process is practically continuous, inasmuch as the recharging of either generator may be accomplished during the "blowing up" of the other, and the time for cleaning out ash and clinker is reduced to a minimum by virtue of the alternating up and down runs in each generator.

By virtue of the provision of the air mixers conventionally shown at 14, a slight modifica-

tion of the foregoing process is possible for manufacturing a gas of intermediate heating value between producer gas and blue water gas, or the combination of blue water gas and coal gas, which is produced by the above method. The heating value of producer gas is from 100 to 150 B. t. u. per cubic foot, while the combination of blue water gas and coal gas, made as above described, will 5 have a value of between 300 and 400 B. t. u. By the following method, a gas of heating value of about 200 to 250 B. t. u. will result, and this is satisfactory for certain manufacturing purposes.

15 Either chamber, 1 or 2, being first charged and heated to incandescence by the air blast through valve 18, is then adjusted with connections for producing water gas, but instead of admitting pure steam, a mixture of steam 20 and air from 14 is admitted either at the lower opening, 13, or at the upper inlet, 12. The result is a producer gas which, upon being led into the other generator and through the fuel mass therein, carries off the volatile 25 elements of said mass, and the resultant gas mixture passes to the gas holder through the water seal, 9, in the usual way.

In this mode of operation, air being supplied with steam, the temperature of the fuel 30 mass in the first chamber is not materially reduced and this step of the operation can be continued for an hour or an hour and one-half during which time the fuel in the second chamber, through which the producer gas is 35 passed, will be thoroughly coked. The fuel mass in the first chamber must then be replenished up to the original depth of about nine feet, and the connections reversed so as to discharge mixed steam and air through 40 the coked mass in the second chamber and transfer the resulting producer gas to the fresh fuel mass and thence to the water seal and receiver.

In this method, the provision of upper and 45 lower connections, 12 and 13, permits making of up and down runs with the mixture of air and steam at will, so that any undue accumulation of ash in the fuel may be prevented by alternating the direction of flow of the 50 gas in the first generator.

Or, if it be desired to make only producer gas, each generator may be operated independently of the other by supplying the mixture of steam and air and leading off the producer gas through the valve, 23, or the valve, 55 28, as the case may be, instead of passing it to the other chamber.

When it is desired to enrich the gas for increasing its illuminating power, the material 60 rich in hydrocarbon, such as tar, fuel oil, and the like, is supplied through injectors, 19, so as to be mixed with the gas coming from the first fuel mass and then to pass in contact with the second fuel mass as the gas flows 65 therethrough on its way to the receiver.

Preferably, the enriching material is added to the water gas above one of the fuel masses before it flows over to the second fuel mass, so that any residual carbon from the tar or oil may be deposited on the incandescent fuel mass in the first chamber and be subsequently decomposed by the steam in the further production of water gas.

It will be recognized that the close coupling of the two generators employed in either form of the process above described insures the conservation of the sensible heat of the gases throughout the process, thus securing efficiency without the addition of such special apparatus as recuperators or stoves.

It should also be noted that the frequent reversal of direction of gas flow through the second mass of fuel, whether it be water gas or producer gas which is applied to said fuel, results in three special advantages. It increases the gas yield from a given amount of fuel, because the carbonaceous material is attacked first from one direction and then from the other, insuring thorough chemical decomposition. It tends to loosen and carry down the ash or clinker formed in the second generator, by virtue of the agitation of the mass produced by alternating the direction of gas movement. And it results in quicker coking of the coal than would be possible with a continuous gas admission in one direction only. Thus the gas output per hour will be increased by reason of this frequent reversal in the second generator.

I claim:—

1. The process of making mixed water gas and coal gas, which consists in providing two masses of coal or like carbonaceous material in separate gas generators, causing partial combustion in one mass until it is heated to incandescence, passing steam for a short time down through said incandescent mass and passing the resultant hot gases directly to and up through the second mass and thence to a gas outlet; then for a short time passing the steam up through the first mass and passing the resulting gases down through the second mass and thence to a gas outlet.

2. The process of making mixed water gas and coal gas as defined in claim 1, which consists in repeating the alternate downward and upward passing of steam through the first mass until the second mass is thoroughly coked by the water gas generated; then replenishing the first mass of fuel while forcing air through the coked second mass to heat it to incandescence, and finally passing steam through the second incandescent mass and thence through the fresh fuel and discharging the resulting gases.

3. The process of making mixed water gas and coal gas as defined in claim 1, which consists in repeating the alternate downward and upward passing of steam through the first mass until the second mass is thoroughly

coked; then replenishing the first mass of fuel, and alternately passing steam down and up through the second coked mass and thence through the first mass, and discharging the resulting gases.

5 4. The process of making mixed water gas and coal gas, which consists in providing two masses of coal or like carbonaceous material in separate gas generators, inducing partial combustion in one of said masses for heating it to incandescence, passing steam alternately down and up through said incandescent mass and directing the resultant water gas through the second mass; said water gas passing alternately up and down through the second mass coincidently with the reversal of the direction of flow of steam through the first mass.

10 5. The process of making mixed water gas and coal gas, which consists in providing two masses of coal or like carbonaceous material in separate gas generators and causing combustion in one mass until it is heated to incandescence, passing steam through said incandescent mass and passing the resultant hot water gas directly through the second mass and thence to a gas outlet; and periodically reversing the direction of flow of said steam and water gas through the system without reversing the order in which the two masses

15 30 are attacked thereby.
